Primary Examiner—Alan P. Douglas*Assistant Examiner*—Robert M. Spear*Attorney, Agent, or Firm*—Willian Brinks Hofer Gilson & Lione**[57]****CLAIM**

The ornamental design for a closure for a container, as shown and described.

DESCRIPTION

FIG. 1 is a front view of a first embodiment of my new design for a closure for a container, the rear view being identical thereto;

FIG. 2 is a side view of the design of FIG. 1;

FIG. 3 is a top plan view of the design of FIG. 1;

FIG. 4 is a bottom plan view of the design of FIG. 1;

FIG. 5 is a longitudinal cross-section view of the design of FIG. 1, taken along line 5—5 in FIG. 3;

FIG. 6 is a front view of a second embodiment of my new design for a closure for a container, the rear view being identical thereto;

FIG. 7 is a top plan view of the design of FIG. 6;

FIG. 8 is a bottom plan view of the design of FIG. 6; and, FIG. 9 is a longitudinal cross-section view of the design of FIG. 6, taken along line 9—9 in FIG. 7.
